Dec. 1798

Henry W. Heuwell, of Philadelphia, Pa.
Letters Patent No. 1798-Dated July 1st 1863.

The schedule referred to in these Letters Patent and making part of the same.

To all whom it may concern:

Be it known that I, Henry W. Heuwell, of Philadelphia, County of Philadelphia, State of Pennsylvania, have invented or produced a new and original design for "Bind Binding"; and I do hereby declare the accompanying drawing, with the following explanation of the same, to form a full, clear and exact description of the said design.

Each edge of the binding is ornamented with a border consisting of a chain with the alternate short and elongated links represented.

Between the borders the binding is ornamented by a series of patterns A, of an oval form, and arranged a short distance apart from each other.

The spaces between the patterns A, are ornamented by patterns B, each being composed of four scrolls as represented.

I claim and desire to secure by Letters Patent the ornamental figures and forms represented in and by the accompanying drawing, the whole forming an ornamental design for blind binding.

In testimony whereof I have signed my name to this specification in the presence of two subscribing witnesses.
